CLAIM

The ornamental design for a combined truck cab and chassis, as shown and described.

DESCRIPTION

FIG. 1 is a perspective view of a combined truck cab and chassis showing my new design, it being understood that the broken lines are for illustrative purposes
only;

FIG. 2 is a side elevational view thereof;

FIG. 3 is a front elevational view thereof; and

FIG. 4 is a side elevational view thereof opposite to that shown in FIG. 2.

The rear of the truck cab is understood to be flat and unornamented.
